HIGH-FREQUENCY ELECTRICAL COMMUNICATION SYSTEM UTILIZING DAMPED OSCILLATIONS

William Arnold Beatty, London W. C. 2, England,
assignor to International Standard Electric
Corporation, New York, N. Y.

Application January 24, 1941, Serial No. 375,814
In Great Britain November 10, 1939

Section 1, Public Law 690, August 8, 1946
Patent expires November 10, 1959

10 Claims. (Cl. 179—15)

1

In the British Patent No. 511,222, there are described various types of pulses used for methods of pulse modulation at a transmitter, while in copending United States application Ser. No. 313,041, filed January 9, 1940, now Patent No. 2,256,336, issued Sept. 16, 1941, are described methods of generating such pulses. In known pulse modulation systems it has been the practice to obtain intelligence in a receiver by discriminating between the intervals of time occurring between the leading and trailing edges of a train of time modulated pulses. In cases where solid pulses such as those coded RS, RL or RT in the aforementioned Patent No. 2,256,336, are transmitted the information can be obtained directly from the pulses, while in cases where double marking pulses coded as D/RS, D/RL or D/RT are transmitted, the leading and trailing edge pulses can in a receiver be utilised to reconstruct solid pulses giving the desired intelligence. In cases where single marking pulses coded as S/RL or S/RT are transmitted the suppressed fixed edge marking pulse can be derived by known means and inserted at the receiver so as to reconstruct the corresponding solid pulses giving the desired intelligence. In all these time modulated pulse systems the intelligence obtained at the receiver is a function of the total time occurring between the leading and trailing edges of a train of time modulated pulse systems, and it is necessary to have information regarding the time of commencement and time of finishing of each individual pulse.

According to the present invention, successive damped oscillations are set up at the transmitter or at the receiver, the amplitudes being determined by the amplitudes at successive instants of a sound or like intelligence wave. The amplitude of each damped oscillation may be determined by the phase of a preceding oscillation at the instant when the damped oscillation is initiated. The oscillations may be generated under the control of a time-modulated pulse train.

The preferred form of the invention utilises pulses which are time modulated as a function of the amplitude of a sound or like wave in such a manner that if required the desired intelligence can be obtained from one edge only of the time modulated pulses. In known pulse systems it has been the practice to have under modulation conditions both the leading and trailing edges of the recurring pulses variable in time, or to have one series of edges fixed and the other series of edges variable in time. In the system to be described the desired intelligence is obtained from

2

variably recurring edges of time modulated pulse, the time modulation however being a very small proportion of the average time of recurrence of said pulses. In this proposal, the variable edge of the new type of pulse will be referred to as the "fluttering edge," while the type of modulation will be referred to as "phased pulse modulation," this choice of descriptive terms becoming apparent from the description which follows.

10 The type of transmission covered by the proposal has the following advantages:

15 Transmission systems in accordance with the invention can be made extremely economical in power, giving a high signal-to-noise ratio; they are very suitable for multiplex transmission and can be readily adapted for secret communication.

20 The operation of the system is dependent upon transmitting a train of pulses so time modulated that they have function characteristic of the amplitude of a sound or like wave, said time modulation being characterised in that the total limits of modulation equal a period of time which is equal to the time taken for a fraction preferably less than $\frac{1}{2}$ of a wavelength period of a radio frequency which is comparatively large compared with the pulse frequency; and at a receiver utilising said pulses to control the interruption of a train of oscillations at a frequency equal to said radio frequency, the intelligence received 30 being a function of the amplitude of the damped oscillations at the end of the pulse trains.

The description which follows may be more readily understood by referring to the accompanying drawing in which:

35 Fig. 1 shows a simple tuned circuit energised by a train of pulses shown in Fig. 2;

Figs. 2, 4, 8 and 18 show various pulse trains required for the system;

40 Figs. 3, 5, 6, 9, 10, 11, 12 and 20 to 24 show oscillation trains developed in carrying out the invention;

Figs. 7, 13, 14 and 19 show circuit arrangements for carrying out the invention;

45 Figs. 15 and 16 illustrate cathode ray tubes utilised for generating certain pulses; and

Fig. 17 shows a multiplex transmission arrangement.

When a simple tuned circuit is excited by a wave of constant rectangular form certain effects 50 readily to be foreseen are noticed.

Referring to the drawing and more particularly to Fig. 1, a simple tuned circuit 31, 32 having for instance a natural frequency of 1 megacycle is shock excited by a rectangular pulse 33 Fig. 2, 55 having a duration of 100 microseconds. The

leading edge 34 of the pulse 33 sets up a train of damped oscillations 35 Fig. 2, the first half-wave of the oscillatory train being shown as a negative cycle. The train of oscillations 35 dies away before the time of occurrence of the trailing edge 36 of the pulse 33, said trailing edge setting up the train of damped oscillations 37 which are similar to the train 35 except that the first half wave of the oscillatory train is shown as a positive cycle; the damped oscillatory trains 35 and 37 in both cases having duration of about 40 microseconds.

If now the circuit 31, 32 is shock excited by a pulse train as shown in Fig. 4 in which the pulses 38 have a duration of approximately 20 microseconds and are separated by time intervals 39 of approximately the same value, and if arrangements are available for accurately altering the relative durations of the pulses 38 and intervals 39 the following effects are obtainable.

Referring to Fig. 5 the damped wave trains 40 are obtained during the duration of the pulses 38 while the damped wave trains 41 are of different amplitude obtained during the interval periods 39, this relationship between the trains 40 and 41 being due to the following effects. Considering the first wave train 40 derived from the edge 42 of the pulse 38 the commencement of this train must obviously be similar to the train 35 derived from the edge 34 of the pulse 33. We have shown that the train 37 is the same as the train 35 except that it is reversed in phase, that is to say, its first half-cycle is positive. The trains 40 are derived from the leading edges 42 of pulses 38 while the trains 41 are derived from the trailing edges 43 of the same pulses, these leading and trailing edges being similar to those of the pulse 33. If the edge 43 tends to set up the train of oscillations 41 during a period of time when the damped train 40 is in phase with the build up tendency for the train of oscillations 41, it can be seen that this train will now have a greater initial amplitude than that shown for the train 37.

If the duration of the pulses 38 are now altered by a slight amount matters can be so arranged that the trains 44, Fig. 6, have such a duration that at the time when the edge 43 tends to set up the train 45 the train 44 is out of phase with the build up tendency of the train 45, the result being that these latter trains have an initial amplitude less than that of the train 37. In practice a change due to pulse duration in the initial amplitude of a train derived from the edge 43 is usually accompanied by an amplitude change in the reverse sense in the train derived from the edges 42 after the first pulse period, since the phasing of the train must modify the next following train thus making the energy content of alternative trains complementary. It can be seen therefore, that taking the two trains 40 and 41 and comparing them with the trains 44 and 45 that practically no change in average amplitude is obtained and these pulse trains are not useful for receiving intelligence in the forms shown in Figs. 5 and 6.

The change of duration for the pulse 38 required to change from train 41 to the train 45 is usually a small fraction of an oscillation period of the shock excited circuit, and in fact when using a shock excited circuit, having a natural frequency of 1 megacycle considerable modulation of the damped train can be obtained with a time modulation of .1 microsecond.

One method of using the features shown above 75

for the purpose of transmitting and receiving intelligence will now be described. In the aforementioned U. S. Patent No. 2,256,336, there are described methods of generating pulses having a time function characteristic of the amplitude of a sound or like wave, one of the types of pulse described in which the leading edges of successive pulses occur at equal time intervals being coded as RL pulses.

The pulses 38 can be considered as a train of RL pulses in which the trailing edges 43 are time modulated so as to be characteristic of the amplitude of a sound wave, the time modulation for maximum to minimum signal amplitude lying within the period of time required to produce the change from train 41 to train 45. Said pulses 38, referring to Fig. 7, used to shock excite the circuit 31, 32 as previously described, the pulses being applied over the terminals 46. One end of the inductance 31 is connected to the grid 47 of the triode valve 48, having cathode 49 and anode 50. A resistor 51 in the grid cathode circuit bypass condenser 52 and terminals 53 and 54 connected thereto complete the circuit as shown. The anode voltage of the valve 48 is such that the valve functions as an anode bend detector under normal operating conditions. The pulses 38 however, in addition to being utilised for shock exciting the circuit 31, 32, are also utilised to change the operating characteristics of the valve 48, this being achieved by feeding the pulses 38 between the terminals 53 and 54, terminal 53 being positive. The increase in bias due to the pulse causing current to flow in the resistor 51 is sufficient to bias the valve 48 well beyond cut off rendering it ineffective as a detector during the duration of the pulses 38. Immediately, on the cessation of a pulse 38 the valve is restored to the operating condition and detects the train of oscillations existing during the following interval 39, and since these trains which will be referred to as interval trains are cyclically varying in their initial amplitudes in accordance with the small percentage time modulation of the pulses 38, the integrated energy of said interval trains is a function of the amplitude of the sound signal responsible for the time modulation of the pulses 38.

It can be seen from the above description that the time modulation of the edge 43 is so small that this edge can be regarded as fluttering, while the functioning at the receiver is dependent upon phasing the fluttering edge with a high frequency oscillation, thus explaining the earlier choice of the terms "fluttering edge" and "phased pulse modulation."

Although the waveforms of Figs. 4, 5, 6 can be used for the transmission of intelligence in the way described, they have been described mainly to indicate the development of prepared systems of greater efficiency and simplicity. In practice there are many advantages to be gained by keeping the duration of the shock exciting pulse a relatively small percentage of the intervals between successive pulses. With the simple type of circuit already described it is of advantage to have the pulse duration very short for instance only 4 microseconds with an interval of 36 microseconds. Such a pulse system and the trains derived therefrom are shown in Figs. 8, 9 and 10.

Referring to Fig. 8, the RL pulse 55 having an average duration of 4 microseconds have leading edges 56 and trailing edges 57, and are separated by interval periods 158 of an average duration of 36 microseconds.

The pulses 55 are time modulated as a function of the amplitude of a sound wave, the edges 57 being caused to flutter as previously described. For the purpose of convenience the type of time modulation required for the operation of the system will be referred to as "flutter modulation." The flutter modulated pulses 55 are utilised to shock excite the simple circuit 31, 32 as previously explained, and referring to Fig. 9 there is shown a damped train of oscillations 58 due to the excitation from the edge 56 of the pulse 55, followed by another damped train of oscillations 59, due to the shock excitation caused by the edge 57 occurring at such a time that the build up tendency of the second train is in phase with the damped train 58.

In Fig. 10 there is shown the condition when the flutter modulation of the edge 57 sets up a condition such that the damped train 60 derived from the edge 56 is out of phase with the build up tendency of the train 61. The trains 59 and 61 both die away prior to the time of occurrence of the next leading edge 56, therefore these trains have no phasing influence on the subsequent trains 58 or 60, these trains being identical under all flutter modulation conditions. Owing to the fact the time modulation of the pulse 55 is very small, the trains derived from the leading edges of the pulses can be regarded as having substantially constant energy; moreover, owing to the short duration of the pulse the trains 58 and 60 will not have been greatly decreased in amplitude at the time of build up of the pulses 59 and 61, and therefore the amplitude of these interval trains can be greatly influenced by the pulse trains which precede them.

When using an arrangement as described having reference to Figs. 8, 9 and 10, it is not necessary at a receiver to suppress the energy in alternate pulse trains, as one train is practically constant, the other being variable as a function of the flutter modulation. It can be seen therefore that in addition to considerable economy in power at the transmitter by having to transmit only a very short pulse, the receiving arrangements can also be simplified.

The arrangements so far described while they permit of the transmission and reception of intelligence, they do not take full advantage of the possibilities of the system. In practical applications it is desirable to arrange at the receiver that the train produced during the duration of the pulse has such a value that it has the maximum effect on the amplitude of the train due to the trailing edge of the pulse. This can be readily achieved by utilising the pulse to drive a regenerative valve circuit into a condition of sustained oscillation and to ensure that the amplitude of this oscillation is such that it can have the maximum effect due to flutter modulation on the change of amplitude of the trains in the interval periods. Sustained pulse trains 62 during the pulse periods followed by trains 63 of large amplitude are shown in Fig. 11 while in Fig. 12 the interval trains 65 due to flutter modulation have practically no amplitude. By trial methods an amplitude of sustained oscillation 62 and 64 can be found such that the interval train can be 100% amplitude modulated by the flutter modulated pulses.

A circuit arrangement shown in Fig. 13 suitable for the production of the wave trains shown in Figs. 11 and 12 will now be described. A triode valve 66 having cathode 67, control grid 68 and anode 69 is connected to a simple regenerative

circuit in which the tuned grid circuit has inductance 70 and condenser 71, and the anode circuit a reaction coil 72. A variable resistor 73 is connected across the tuned grid circuit, the grid condenser 74 grid leak resistor 75 and input terminals 76 and 77 complete the circuit.

The flutter modulated pulse 55 is fed to the terminals 76 and 77, the former being positive, the amplitude of the pulse being sufficient to set the circuit into sustained oscillation. Oscillations quickly build up in the valve circuit reaching a steady value, as shown by the trains 62 and 64, when the anode supply derived from the pulse is rapidly switched off by the trailing edge 57 a damped train of oscillations is set up in the tuned grid circuit, these oscillations being shown as 63 Fig. 11 and 65, Fig. 12, their amplitude being dependent upon the phasing of the edge 57 relative to the sustained oscillation as previously explained. The damping of the trains 63 and 65 is regulated by the variable resistor 73. The trains of oscillations in the circuit 70, 71 can be coupled in any well known manner to a suitable detector, giving the desired sound intelligence characteristic of the sound wave responsible for the flutter modulation of the pulses 55.

A circuit suitable for detecting the trains of oscillations in the circuit 70, 71 of Fig. 13, and at the same time separating the sustained pulse trains 62 for the varying damped trains 63, 65 is shown in Fig. 19.

Varying damped trains are obtained from a train of RL pulses in a similar manner to that described for Fig. 13 by means of valve 149 having anode 141, control grid 142, and cathode 143, with a bias resistance 144 and bias by-pass condenser 145, grid leak 146, grid condenser 147, and a tuned grid circuit consisting of condenser 148 and inductance 149 coupled inductively to a reaction winding 150 in the anode circuit. If RL pulses, Fig. 20, are applied to terminals 151 and 152, the latter being made positive, a sustained oscillation and its accompanying damped train will be formed, Fig. 21, the degree of damping being adjusted by resistance 153. This is then fed into valve 156 which with its associated components forms the first step in separating the continuous train from the damped train.

The mechanism of this second stage, consisting of valve 156 having anode 157, suppressor grid 158, screen grid 159, control grid 160 and cathode 161, with anode resistance 162, bias resistance 163, bias by-pass condenser 164 and grid resistance 155 is as follows. The anode resistance 162 is connected to a steady H. T. supply, and the signal train, Fig. 21, is fed to the control grid 160 via condenser 154. The operating conditions of the valve 156 are then caused to vary in synchronism with the RL pulses supplied to terminals 151 and 152, by connecting the screen grid 159 to terminal 152, so that, during the duration of the positive pulse 165, Fig. 20, while the sustained pulse train is being generated in valve 149 and its associated circuit, the anode current of valve 156 is increased, so causing its anode voltage to drop, with the result that the output from valve 156 is as shown in Fig. 22. It should be noted that the residual voltage V_1 , Fig. 20, between the positive pulses 165 must be such that valve 156 will amplify the damped train 166, Fig. 21, but will not permit valve 149 to oscillate.

The output from valve 156 is now fed into a leaky grid detector stage consisting of valve 167 having anode 168, control grid 169, and cathode 170 with anode resistance 171, grid leak 172 and

grid condenser 173 so arranged that the damped train 189, Fig. 22, is rectified, while the negative pulse extends past the cut-off point of valve 167 so that the continuous train portion of the signal 190, Fig. 22, is eliminated and the output from valve 167 is as shown in Fig. 23, section 175 appearing as a positive pulse.

This positive pulse appearing between the rectified damped trains can now be cancelled by feeding the signal to the anode of valve 175 through a condenser 174. Valve 175, consisting of anode 177, suppressor grid 178, screen grid 179, control grid 180 and cathode 181, together with anode resistance 182, cathode resistance 183 and cathode by-pass condenser 184 is made to develop a negative pulse across its anode resistance 182 equal to the signals positive pulse 175, Fig. 23, and in synchronism with it, by feeding the original positive pulse from terminal 152 to its control grid 180 via resistances 185 and 186, the latter being made variable to facilitate exact adjustment. The output voltage now appearing at terminals 187 and 188 is as shown in Fig. 24 being the rectified damped train only, as required.

The applications so far described depend upon the time modulation of the pulse being such that the actual duration of the pulse is changed, but the system can also be made to operate by slightly changing the time of occurrence of a pulse which itself remains of constant duration. In the previously mentioned U. S. Patent No. 2,256,336, there are described various types of marking pulses of relatively short duration but occurring at varying intervals of time, the variations in said time intervals being a time function of the amplitude of a second or like wave. If the time of occurrence of the above type of pulse is varied within the limits of the flutter modulation already described, such pulses can with special receiving arrangements be utilised for the purpose conveying intelligence. For the purpose of convenience such pulses will be referred to as "fluttering pulses."

The operation of the system with fluttering pulses can be more readily understood by referring to the receiver circuit shown in Fig. 14. A radio frequency supply source 78 is connected to a blocking circuit 79, so arranged that it allows radio frequency energy to be transferred to the tuned circuit 80, 81 under the control of a fluttering pulse, the blocking circuit being released for the pulse duration. This blocking action may be performed in a manner known in the art, for example, by control of the grid bias or plate potential of an amplifier tube. A variable damping device 82 which may be a thermionic valve is connected across the tuned circuit 80, 81, the characteristics of the device, also under the control of the fluttering pulses being such that during the duration of the pulse the circuit is lightly damped while during the intervals between pulses the circuit is heavily damped. This can be achieved utilising the pulse to back bias (i. e. to apply a negative bias) during the pulse period a thermionic valve connected as a load across the circuit 80, 81 and to allow the valve to assume a low impedance during the intervals between pulses.

The circuit 80, 81 is loosely coupled to the tuned circuit 83, 84, which has a variable damping resistor 85 connected across it. The circuit 83, 84 is connected between the cathode 86 and control grid 87 of the valve 88 which has an anode 89. A reaction coil 90 is connected between the anode

88 and the terminal 91. The cathode 86 is connected to the terminal 92, the condenser 93 and grid leak 94 completing the circuit. The coupling between the coils 83 and 90 is such that when H. T. is applied to the valve 88 the circuit does not oscillate. The operation of the arrangements is as follows.

Assume that the pulses 55, Fig. 8 are fluttering pulses, and that they are simultaneously fed to 10 the blocking circuit 79, the damping device 82 and as an H. T. supply to the valve 88. A pulse 55 releases the blocking circuit 79 allowing radio frequency energy to be fed from the source 78 to the circuit 80, 81, at the same time the damping on the circuit 80, 81, is removed by means of the variable damping device 82, allowing a sustained oscillation to be built up in the circuits 83, 84 and 83, 84; the valve 88 serving to amplify this oscillation, since it simultaneously received 20 an H. T. supply from the pulse 55. The oscillations in the circuit 83, 84 have a definite phase relationship to the oscillations in the supply source 78, which is maintained in a stable condition both as regards frequency and phase drift. 25 When the fluttering pulse ceases this time of cessation has such a relationship to the phase of the oscillations in the circuit 83, 84, as to set up a train of oscillations similar to those shown at 33 and 65 in Figs. 11 and 12. For correct operation it is necessary that the pulse 55 in the unmodulated condition has such a phase relationship with the oscillations in the circuit 83, 84 as to set up an interval train which has an energy content which is the mean of the energy contents 35 of the trains 63 and 65. This correct phase relationship between the pulse 55 and the radio frequency oscillations can be obtained by adjusting the coupling between the circuits 80, 81 and 83, 84, or by the introduction of any known 40 phasing device between the supply source 78 and the circuit 82, 84.

On the cessation of a pulse 55 the damping device 82 rapidly damps the oscillations in the circuit 80, 81 and this circuit therefore has little 45 influence on the damped train set up in the loosely coupled circuit 83, 84.

The fluttering pulse system has an advantage over the flutter modulation system in that the system cannot give intelligence to ordinary amplitude modulated receivers. The system also offers a high degree of secrecy since the amplitude of the flutter of the fluttering pulse or flutter modulation for 100% amplitude modulation must be associated with a definite frequency 55 for the shock excited circuits in the receiver. Therefore for reception purposes, in addition to being familiar with the general method employed it is also necessary to know what particular frequency to use in the shock excited circuits.

Owing to the fact that flutter modulated, or fluttering pulses occur at substantially equal time intervals, use can be made of this fact to reduce at receivers the liability to interference by short duration random signals having an intensity 65 greater than that of the pulse signal.

It has been already shown that the actual duration of a pulse is not important for the setting up of the desired damped trains, for instance pulses having a duration of approximately 4 microseconds can be used with interval periods of 36 microseconds, or pulses of approximately 2 microseconds with intervals of 38 microseconds will give practically the same final result.

Assuming a transmitted pulse of approximately 4 microseconds and interval of approxi-

mately 36 microseconds, at the receiver a shorter fluttering pulse for instance, 2 microseconds with intervals of 38 microseconds can be obtained by feeding the pulses through a delay circuit having a delay of approximately 42 microseconds and combining each delayed pulse with the next succeeding undelayed pulse. This method can be extended by employing a second delay circuit having a delay of approximately 82 microseconds, and combining this delayed pulse with the previously derived pulse. Methods of combining delayed and undelayed pulses are described in British Patent No. 528,192.

The delay circuits for the above purpose are well known, but in cases where it is required to accurately adjust the duration of the derived pulse, this can be done by having a vernier delay arrangement in series with the more usual delay circuits. Such vernier delay or phasing arrangement can be an electronic device, utilised as described in British Patent No. 519,747.

The utilising of delayed and undelayed pulses at the receiver makes the system practically free from interference occurring at random intervals no matter how intense this interference may be.

In addition to the above expedient, an amplitude limiter may be used in a receiver, matters being so arranged as is usual in pulse transmissions to utilise only the tips of the transmitted pulse, for the purpose of establishing the received intelligence.

The proposals so far described utilise flutter modulated pulses or fluttering pulses in which the time modulation is a very small percentage of the time of recurrence of such pulses. The phase pulse system can also be applied for the purpose of discriminating between rectangular pulses of constant amplitude but of widely differing durations, as for instance line and frame pulses in television synchronising systems.

In a known television system line pulses have a duration of ten microseconds while the frame pulses comprise a train of pulses having a duration of 40 microseconds. If such pulse are utilised to shock excite a tuned circuit for instance according to the type described having reference to Fig. 13, the natural frequency of the shock excited circuit can be such that the train of pulses set up at the end of the 40 microsecond frame pulse is of the type shown in Fig. 11, while the train set up at the end of the 10 microsecond line pulse is of a smaller amplitude for instance, as shown in Fig. 12.

The fact that any desired phasing between a high frequency signal and pulses of different durations may be obtained can be readily appreciated by taking a simple example. If we assume that during the period of a line pulse i. e. 10 microseconds the frequency of the shock excited circuit is such that an integral number of oscillations plus a half oscillation occur, then during the period of a frame pulse i. e. 40 microseconds, an integral number of oscillations take place, therefore the trailing edge of the line pulse can be regarded as 180% out of phase while the trailing edge of the frame pulse, and the damped trains following these respective pulses will have different amplitudes.

It should therefore be obvious that by suitably choosing the frequency of the shock excited circuit the amplitude of the trains of oscillations, at the end of one pulse can be made larger than the other, and for the purpose of obtaining accurate frame synchronisation matters are so arranged that the damped train at the end of the

frame pulse has the larger amplitude. The damped trains are now fed to a detector and amplitude filter so arranged that an output can only be obtained from trains of larger amplitude, said output being utilised for frame synchronising.

This method of pulse discrimination can also be applied in cases where discrimination is required between one or more pulses of a pulse train having pulses which have three or more different durations.

For instance, if it is required to use the shortest and the longest pulse of a train of three pulses of different durations, for the purpose of synchronising apparatus, a suitable frequency can be found such that the amplitude of the trains at the end of the shortest and longest pulses is greater than the amplitude at the end of the other pulse, and as described above the shortest and longest pulses can be used for synchronising.

It can therefore be seen that this method of pulse discrimination is much more flexible than known systems.

The system can also be applied to pulses in which one edge is flutter modulated giving one kind of intelligence while the other edge is time modulated as described in the afore-mentioned U. S. Patent No. 2,256,336

It is therefore possible for one kind of intelligence to be conveyed by the flutter modulation of one edge and for another kind of intelligence to be conveyed by the ordinary time modulation, and if the latter modulation is comparatively large it will entirely mask the flutter modulation intelligence in ordinary amplitude modulated receivers which however, will give intelligence from the ordinary time modulated pulse. For instance, if the pulses coded as RT in U. S. Patent No. 2,256,336, that is to say rectangular pulses having their trailing edges occurring at equal time intervals and their leading edges occurring at varying time intervals, are modified in such a manner that the trailing edge is caused to flutter two kinds of intelligence can be simultaneously transmitted by one pulse. This type of pulse transmission will for the purposes of convenience be coded as RFT (rectangular with fluttering trailing edge the leading edge being variable), the corresponding RL pulse being coded as RFL.

Such a system may be utilised for stereophonic transmission, the separate sound waves constituting the two kinds of intelligence.

A method of generating such a double intelligence pulse system will now be described. Referring to Fig. 11 of the drawing accompanying U. S. Patent No. 2,256,336, there is shown a target arrangement of the cathode ray tube which is suitable for generating pulses of constant duration but having varying times of occurrence, such pulses being utilised as marking pulses indicating the leading edges of solid pulses. Using similar method to those described in the above-mentioned U. S. patent, fluttering pulses can be generated, the flutter being characteristic of the amplitude of a sound wave. Referring to Fig. 15 of the drawing accompanying this specification there is shown a target 193 of a cathode ray tube arrangement 194 similar to that described having reference to the Fig. 11 of U. S. Patent No. 2,256,336. The target plate 193 is shown as a straight edged plate disposed nearly at right angles to the direction 195 of scanning. This arrangement of target plate ensures that for large amplitudes of transverse

modulation of the beam due to the amplitude of the sound wave a relatively small time modulation of the desired pulses is obtained. The same linear scanning source which causes the scanning of the target 96 is also used to scan the target 96 of a similar cathode ray tube arrangement 97 in the direction 98. The beam in this second tube being transversely modulated under the control of the amplitude of another sound wave. We now have a train of pulses of constant duration occurring at considerably varying time periods obtained from the tube 97, while we have another fluttering train of pulses obtained from the tube 94. These two marking pulse trains can in any known manner be utilised to establish solid type pulses which can be transmitted, or alternatively the pulses can be transmitted as a double pulse system, and the corresponding solid pulses reconstituted at the receiver.

Whichever of these methods is adopted the resulting RFT pulses can be utilised to give in ordinary amplitude modulated receivers intelligence corresponding to the sound wave causing the time modulation of the pulses derived from the target 96, while the fluttering edge of the RFT pulses can be utilised to give with a special receiver intelligence corresponding to the sound wave causing the fluttering of the pulses obtained from the target 93. The receiver required for obtaining the intelligence from the fluttering edge of the RFT pulse is similar to that described having reference to Fig. 14, except that the detector circuit not shown, associated with the tuned circuit 83, 84 is made inoperative during the duration of the pulse; this can be done in a manner similar to that shown in Fig. 7.

The time modulation of the RFT pulses should be kept within such limits that the variable edge of one pulse does not approach too close to the fluttering edge of the preceding pulse, since sufficient time must be allowed for the interval train of oscillations to die away before the commencement of the succeeding pulse. This requirement to some extent limits the depth of time modulation which can be given to the pulse. The RFT pulse above described although capable of simultaneously giving two kinds of intelligence, is to some extent subject to weak cross time modulation of the flutter intelligence on the time modulation intelligence. In practice this is not serious as the flutter time modulation is generally very much less than the main time modulation. This tendency to cross time modulation can however, be obviated by arranging that a train of RT pulses having a time function characteristic of one kind of intelligence, are fluttered so that they have a flutter characteristic of another kind of intelligence. These pulses will for the purpose of convenience be coded as RT+F (rectangular pulses with trailing edge normally fixed and leading edge variable, the leading and trailing edges being fluttered modulated in phase by similar amounts).

A method of generating the RT+F pulses will now be described, this being a modification of the method used for generating RFT pulses. As described for the generation of RFT pulses a flutter modulated pulse train is derived from the plate 93, and these pulses are utilised to synchronise a second time base giving a linear waveform suitable for scanning the target 96. The flutter time modulation can be less than 1% of the average time of recurrence of the pulses and therefore no difficulty is experienced in maintaining the

second time base in synchronism with the fluttering pulses. The effect of using a second time base is to advance or retard the normal time of occurrence of the variable edge marking pulses in accordance with the flutter modulation of the leading edge marking pulses. It will be seen that the type of pulse established by this method has the leading edge occurring at nearly equal intervals while the trailing edge occurs at widely varying intervals, whereas at the receiver the opposite condition should hold. The type of pulse which has been generated will for the purpose of convenience be coded as RL+F and this can at the transmitter or receiver be readily changed to an RT+F pulse by passing the pulse through a single stage valve amplifying stage which also changes the phase of the pulse. Such changing of pulse phase does not affect the intelligence which is obtained from an amplitude modulated receiver but has, however, the effect of changing the flutter control edge from being a leading edge to a trailing edge. The RT+F pulses are utilised in a similar manner for the purpose of shock exciting a suitable receiver circuit as has been described for the RFT pulses. This latter method of transmission has the advantage that both kinds of intelligence can be transmitted without the possibility of mutual interference, and if the existence of the flutter modulation is not suspected, the intelligence due to the flutter modulation will not be detected.

Owing to the fact that only one train of pulses having a duration which is relatively small compared with the interval between successive pulses and which do not vary greatly in their time of recurrence, is required for the transmission of intelligence, the system is particularly suitable for the multiplex transmission of intelligence over one channel, since by selective allocation of time intervals to different channels different flutter modulated, or fluttering pulses can be allocated to said channels.

One method of performing multiplex transmission will be more readily understood by referring to Figs. 16, 17 and 18. A cathode ray tube 99 Fig. 16, has 8 similar pairs of target plates the plates of each pair being arranged one behind the other. The plate 100 is larger than the plate 101 and is placed behind it as shown. Plates 100, 102, 104, 106, 108, 110, 112 and 114 are utilised as circuit switching plates, while the smaller plates 101, 103, 105, 107, 109, 111 and 113 are used for the purpose of generating flutter modulated pulses. The plates as shown have parallel sides, this particular shape being taken for exemplary purposes only. Electrostatic deflecting means are available in the cathode ray tube, and an electron beam follows a circular path 137 across all the switching and modulating plates. The alternating current source 116, Fig. 17, supplies current at a frequency equal to the desired pulse frequency to an amplitude modulating unit 117 and a phase splitting unit 138, whence the alternating current is fed in phase quadrature to the deflecting plates 65 of the cathode ray tube 99 giving the trace 137 already mentioned.

One of the blocking circuits 118-125 is interposed between each source of intelligence 126-133, a separate blocking circuit being allocated to each intelligence source. Normally the several blocking circuits operate to prevent signals from the various intelligence sources from reaching the modulating unit 117.

Considering the electron beam in the tube 99 just before it strikes the plate 100, the operation

is as follows. The beam is not resting on any plate and in this condition all the blocking circuits are operative. Immediately the beam strikes plate 100 a pulse is derived therefrom and this pulse can be utilised to trigger a double stability circuit of known type setting up the pulse 134, Fig. 18. The pulse 134 serves to so bias the blocking circuit 118 that it becomes inoperative and allows the signal intelligence from source 126 to pass to the modulating unit 117, thereby changing the amplitude of the alternating current from the source 116 in accordance with the amplitude of the signal from the source 126. Assuming that the change in amplitude is such that the signal fed in phase quadrature from the unit 138 decreases the diameter of the trace 137 then the beam as it passes over plate 101 takes a longer period of time to pass completely across the plate than would be the case when no modulation was taking place. Alternatively, if the modulation should increase the diameter of the trace 137, the result will be for the beam to take a shorter period of time than normal to cross the plate 101. The electron beam therefore crosses the plate 101 giving a pulse having a duration which is a time function of the amplitude of the signal from the source 126. Immediately the beam leaves the plate 101 it once more strikes plate 100 giving another pulse serving to trigger the double stability circuit in the reverse direction and thus discontinuing the pulse 134, whereupon the bias is removed from the blocking circuit 118 thereby making this circuit operative once more and cutting off the signal intelligence from the source 126.

The electron beam continues on its travel and after a very short time period strikes the switching plate 102 setting up via another double stability circuit the pulse 135, which serves to unblock the circuit 119, allowing the signal from the source 127 to pass to the modulating unit 117, modifying the diameter of the trace 137 in such a manner that the pulse derived from plate 103 has a time function of the amplitude of the signal from source 127. The beam now once more strikes plate 102 discontinuing pulse 135. The other intelligence channels operate in a similar manner, the pulse 136 for the pair of plates 114 and 115 only being shown in Fig. 18.

The shape of the individual signalling plates 101, 103, etc. may be modified so that any desired law is obtained. There are advantages in making each signal plate follow a different modulation law to the other, as by this means different frequencies for the shock excited circuits can be chosen at a receiving point, thus reducing the possibility of mutual interference between the damped trains generated in a number of receivers located close to one another.

At the receiving end a similar tube to the tube 99 can be provided, having eight switching plates disposed in a similar manner to the switching plates in tube 99, and a source of supply of the same frequency as that of 116 can be utilised to set up a circular trace giving switching pulses from the various plates. The current giving this circular trace can be suitably phased by any known means so that the receiver switching pulses synchronise with the appropriate transmission channel. The pulses generated at the receiver are utilised to cyclically allocate in any known manner the various flutter modulated pulses to different intelligence channels thus allowing of multiplex operation.

If desired synchronising of the transmitter and

receiver pulse frequency can be achieved by utilising one of the communication channels to transmit a frequency which is submultiple of the frequency in the source 116. This signal can at the receiver be put through a suitable frequency multiplier giving the desired controlling frequency at the receiver.

Owing to the fact that only a very small change in the duration of the pulse is required for the transmission of intelligence, the system can be readily applied to signalling systems which already utilise pulses for other purposes, such systems being for instance television systems.

In pending United States application Ser. No. 325,954, filed March 26, 1940 now Patent No. 2,295,023, issued Sept. 8, 1942, it is proposed that the line or frame synchronising pulses of a television signal to be time modulated to convey additional information such as brightness level, frame sequence for colour or stereoscopic television, or degree of volume compression of an associated signal.

It is now proposed that flutter modulated pulses be utilised to achieve similar effects. Methods of applying flutter modulated pulses for such purposes should now be obvious having regard to the foregoing and also having regard to said U. S. Patent No. 2,295,023. In addition to giving the types of additional intelligence above mentioned, it is possible to effectively use flutter modulated pulses as combined line synchronising pulses, and sound intelligence for the accompanying vision signal. In such cases it is necessary to have the leading edge of the synchronising pulse occurring at equal intervals of time, while the trailing edge is flutter modulated as already explained. If desired certain of the pulses occurring in a frame period can also be flutter modulated so as to also give sound intelligence during this period.

The phase pulse modulation system above described has many advantages when it is desired to communicate over distances in which the time taken for signals to travel from one point to another remains reasonably constant relative to the frequency of the shock excited circuit in use at the receiver. The system however, is not suitable for transmitting over distances which due to ionospheric or atmospheric reflection or refraction change to a great extent the length of the path followed by signals between a transmitter and receiver. It will therefore be seen that the most useful applications of the system are for communicating on ultra short waves within distances governed by the limitations of such short wave transmissions. Ultra short waves are necessary so as to easily obtain the necessary wide bands required for the transmission and reception of the pulses.

The system can also be readily applied to cable systems provided the cable can accommodate the wide band of frequencies required for the transmission.

What is claimed is:

1. An electrical system for the transmission of intelligence comprising means for producing a succession of damped oscillations and control means comprising means responsive to the phase of a preceding oscillation at the instant when the damped oscillation is initiated for controlling the amplitude of successive ones of said oscillations in accordance with the amplitudes at successive instants of a sound or like intelligence signal wave.

2. A system according to claim 1, further comprising means for applying a time modulated pulse

75

train to control said means for producing a succession of oscillations.

3. An electrical system for the transmission of intelligence, comprising means for producing a succession of damped oscillations, control means for controlling the amplitude of successive ones of said oscillations in accordance with the amplitudes at successive instants of a sound or like intelligence signal wave, means for applying a time modulated pulse train to control said means for producing a succession of oscillations, said pulse train comprising pulses of a frequency substantially greater than the highest signal wave frequency, and means for variably controlling the pulse duration in accordance with signal wave amplitude and over a range which is comparable with the period of said damped oscillations.

4. An electrical system for the transmission of intelligence, comprising means for producing a succession of damped oscillations, control means for controlling the amplitude of successive ones of said oscillations in accordance with the amplitudes at successive instants of a sound or like intelligence signal wave, means for applying a time modulated pulse train to control said means for producing a succession of oscillations, said pulse train comprising pulses of a frequency substantially greater than the highest signal wave frequency, and means for variably controlling the pulse duration in accordance with signal wave amplitude and over a range which is comparable with the period of said damped oscillations, the duration of said pulses being small with respect to their time spacing.

5. A transmitter, comprising means for generating a train of time-modulated pulses of high frequency, means for varying the duration of said pulses in accordance with the amplitude of a signal wave, and over a range less than the period corresponding to the fundamental pulse frequency, means for producing a succession of damped oscillations under control of said time modulated pulses, and means for limiting the amplitude of successive ones of said oscillations in accordance with the amplitudes of successive instants of said signal wave.

6. A receiver for pulse modulation systems including means for producing a succession of damped oscillations comprising a resonant circuit, means for applying thereto a received time modulated pulse train for causing the shock-excitation thereof, the frequency of said circuit being high with respect to the fundamental pulse frequency of said pulse train and the damping being such that the oscillations have substantially died away at each instant of arrival of a pulse whatever the duration of the previous pulse.

7. An electrical system for the transmission of intelligence, comprising means for producing a succession of damped oscillations, control means for controlling the amplitude of successive ones of said oscillations in accordance with the amplitudes at successive instants of a sound or like intelligence signal wave, means for applying a train of pulses to control said means for producing a succession of oscillations and means for variably controlling the spacing of one edge of successive ones of the pulses of said train in time in accordance with the amplitude of a sound or like intelligence wave.

8. An electrical system for the transmission of intelligence, comprising means for producing a succession of damped oscillations, control means

for controlling the amplitude of successive ones of said oscillations in accordance with the amplitudes at successive instants of a sound or like intelligence signal wave, means for applying a time modulated pulse train to control said means for producing a succession of oscillations, means for varying the spacing of leading edges of the pulses of said train from equally spaced time intervals in accordance with the amplitude of one signal, and means for varying the spacing of trailing edges of said pulses from equally spaced time intervals in accordance with the amplitude of a second signal wave.

9. An electrical system for the transmission of intelligence, comprising means for producing a succession of damped oscillations, control means for controlling the amplitude of successive ones of said oscillations in accordance with the amplitudes at successive instants of a sound or like intelligence signal wave, means for applying a time modulated pulse train to control said means for producing a succession of oscillations, means for varying the spacing of leading edges of the pulses of said train from equally spaced time intervals in accordance with the amplitude of one signal, and means for varying the spacing of trailing edges of said pulses from equally spaced time intervals in accordance with the amplitude of a second signal wave, the time intervals being determined by one set of edges or marking pulses varying over a range comparable with the interval between the equally spaced time instants and the time intervals determined by the other set of edges or marking pulses varying over a relatively small range.

10. A multiplex system for the transmission of intelligence, comprising means for producing a succession of damped oscillations, control means for controlling the amplitude of successive ones of said oscillations in accordance with the amplitudes at successive instances of a number of intelligence signal waves, means for applying a time modulated pulse train to control said means for producing a succession of damped oscillations, and means for variably controlling the pulse duration in accordance with the signal wave amplitudes and over a range which is comparable with the period of said damped oscillations, said last mentioned means comprising means for deflecting an electron beam in a circular trace by high frequency alternating currents in quadrature, a plurality of target structures arranged in the path of said beam to be cyclically scanned by the beam, said target structures being designed to present different traversal areas at different radial displacements, means for controlling the amplitude of the deflection of said beam in accordance with each of said number of signal waves over successive periods determined by the incidence of the beam on successive target structures, and means for collecting from the target structures the determined current pulses of varying duration determined by the momentary radius of the trace.
